UNITED STATES PATENT OFFICE.

BYERS W. KADEL, OF BALTIMORE, MARYLAND, ASSIGNOR TO THE SYMINGTON COMPANY, OF NEW YORK, N. Y., A CORPORATION OF MARYLAND.

SIDE FRAME.

Application filed May 5, 1925. Serial No. 28,071.

To all whom it may concern:

Be it known that I, BYERS W. KADEL, a citizen of the United States, residing at Baltimore, in the State of Maryland, have invented certain new and useful Improvements in Side Frames; and I do hereby declare the following to be a full, clear, and exact description of the invention, such as will enable others skilled in the art to which it applies to make and use the same.

This invention relates to side frames for railway car trucks and more particularly to the construction of those portions of a cast side frame with integral journal boxes adjacent the ends of the frame.

The principal object of my invention, generally considered, is the reinforcement of the union between integral journal boxes at the ends of a cast side frame for railway car trucks.

An object of my invention is the strengthening of the juncture between journal boxes formed at the ends of side frames for railway car trucks by carrying flanges on upward above the top of each box and forming said flanges in line with the general direction of the tension member.

Another object of my invention is the strengthening of the connection between integral journal boxes formed at the ends of side frames for railway car trucks with said side frames and particularly in connection with cast frames in which the compression and tension members are formed generally U-shape in cross-section and in which each member comprises a web and flanges at opposite sides of said web, ribs being provided in line with the web of the tension member, extending from below the top of each journal box to above the top thereof and slightly clearing the upper inner corner of each journal box whereby the union between each journal box and the frame is strengthened.

Another object of my invention is the provision of reinforcing ribs on the sides of side frames for railway car trucks, said ribs being located adjacent a journal box and extending across the outer faces of the side walls of the box portion of the frame above the journal box from the tension member below the top of the journal box and preferably being swelled or increased in depth at approximately the corner of the respective journal box.

Other objects and advantages of the in-

vention will become apparent as the description proceeds.

Referring to the drawings illustrating my invention, the scope whereof is pointed out in the claims:

Figure 1 is a fragmentary side elevation of one end of a side frame for railway car trucks embodying my invention.

Figure 2 is a fragmentary plan view of a side frame such as shown in Figure 1.

Figure 3 is a partial cross-sectional view of the side frame taken on the line 3-3 of Figure 1 and looking in the direction of the arrow.

Referring to the drawings in detail, similar reference characters designating like parts in the various views, I have shown one end of a side frame 1 for railway car trucks, the remainder of said frame, not involving features of my present invention, not being illustrated.

Such a frame may comprise a compression member 2 and tension member 3, the ends of said compression and tension members being integrally united at 4, as is usual in side frames and preferably formed with a journal box 5 adjacent each union of compression and tension members.

The frame, as will be understood, is symmetrical on either side and may be formed as is usual, with bolster column guides or strut portions spacing intermediate portions of the compression and tension members. Such features, however, are not part of my invention and as they are well known to those skilled in the art, it is not considered necessary to further illustrate them.

As will be understood, the compression member 2 and tension member 3 extend substantially the full length of the side frame and at each end of said side frame is a journal box 5. Said compression and tension members are each formed generally U-shape in cross-section with a main web portion 6 and flanged portions 7 on opposite sides of the web portion, said flanged portions, in the embodiment shown, extending inwardly or toward each other. The outer edges of the flanged portions 7 may be thickened or provided with a rib or bead portion 8 extending therealong. It will be apparent that in the present embodiment, the tension member is formed with a bottom web and upstanding flanges at opposite sides of said web.

The outer portions of the web 6 of the

compression member 2 are preferably sloped downwardly and outwardly and curved to connect with the outer wall of each journal box 5 at 9. In other words, the outer portion of the web of the compression member is curved at its outer ends from an approximately horizontal to an approximately vertical position where it merges with the outer wall of a journal box at 9. However, the construction may be lightened, if desired, by cutting away a portion of the web 6 of the compression member adjacent the connection with the journal box, as illustrated particularly in Figure 2 adjacent the reference character 9.

The corresponding flanged portions 7 of the compression and tension members 2 and 3 merge into each other at 10 to form a box-like portion, as illustrated, over each journal box. The union between the web 6 of the tension member 3 and the journal box 5 is preferably made by curving said web slightly at 11 to approximately horizontal position and joining it with the roof or upper wall 12 of the journal box, as illustrated. The central portion of the web at this point may be cut away, if desired, to lighten the construction.

Approximately triangular reinforcing webs 13 may be provided between the under portion of the web 6 of the tension member and the inner wall 14 of each journal box, as is usual. The connection between each journal box and the corresponding end of the side frame is reinforced by flanges or rib portions 15 in line with the general plane of the web 6 of the tension member and extending along the flanged portions thereof outwardly and upwardly beyond the top of the journal box. These flanges or ribs 15, as illustrated, preferably clear the inner corner of each journal box and are carried upwardly in a diagonal line across the outer faces of the side walls of the box portion of the frame above the journal box. These ribs or flanges 15 may be formed on the outside or inside of the side frame or on both sides thereof, as illustrated most clearly in Figure 2. As there shown, the depth of each rib 15 is greatest adjacent the upper inner corner of the journal box and tapers or decreases therefrom both ways to merge with the side walls of the frame. Although these flanges 15 are shown preferably swelled or increased at their intermediate or central portions by increasing the depth thereof, I do not wish to be restricted to this particular construction because their width may be increased as well as their depth or may be increased while their depth remains substantially constant, merely tapering slightly at the extreme ends.

By virtue of the aforescribed construction, it will be apparent that the union between each journal box and the correspond-

ing end of the side frame is greatly strengthened and rigidified by the reinforcing flanges or ribs 15 extending at the critical portion of the connection at each end of the frame.

Having now described my invention, what I claim is:

1. A car truck side frame comprising a compression member and a tension member, said members converging at their ends and united together and to journal boxes, the joints between said members and journal boxes being reinforced by flanges from the sides of the tension member extending from below to above the tops of said journal boxes.

2. A car truck side frame comprising a compression member and a tension member, said members converging at their ends and united together and to journal boxes, the joints between said members and journal boxes being reinforced by flanges disposed generally in line with the lower portion of the tension member and extending along said tension member beyond the junctions with said journal boxes.

3. A car truck side frame comprising a compression member and a tension member, said members converging at their ends and united together and to journal boxes, the joints between said members and journal boxes being reinforced by flanges extending adjacent the junctions between the tension member and journal box, but clearing the adjacent corners of the journal boxes.

4. A car truck side frame comprising a compression member and a tension member, said members converging at their ends and united together and to journal boxes, the joints between said members and journal boxes being reinforced by flanges extending from those portions of the tension member adjacent the journal boxes, diagonally upward across the outer face of the side walls of the portions of the side frame above the journal boxes.

5. A car truck side frame comprising a compression member and a tension member, said members converging at their ends and united together and to journal boxes, the joints between said members and journal boxes being reinforced by ribs extending along the faces of the side frame between the tension member and those portions of the side frame above the journal boxes, said ribs being increased in strength adjacent the upper inner corners of the journal boxes, and decreasing therefrom to their ends.

6. A car truck side frame comprising a compression member, a tension member generally U-shape in cross section, formed with a bottom web and upstanding flanges at the sides of the web, and a journal box at each end of the frame and joined thereto adjacent the junction of the compression and tension members, the junctions between the frame

and journal boxes being reinforced by flanges from the sides of the tension member in line with the web thereof and extending from below to above the tops of said journal boxes.

7. A car truck side frame comprising a compression member, a tension member, generally U-shape in cross-section, formed with a bottom web and upstanding flanges at the 10 sides of the web, and a journal box at each end of the frame and joined thereto adjacent the junction of the compression and tension members, the junctions between the frame and journal boxes being reinforced by ribs 15 disposed generally in line with the web of the tension member and extending along said tension member beyond the junctions with said journal boxes.

8. A car truck side frame comprising a 20 compression member, a tension member, generally U-shape in cross-section, formed with a bottom web and upstanding flanges at the sides of said web, and a journal box at each end of the frame and joined thereto adjacent 25 the junction of the compression and tension members, the junctions between the frame and journal boxes being reinforced by flanges extending adjacent the junctions between the tension member and journal box 30 but clearing the adjacent corners of the journal boxes.

9. A car truck side frame comprising a

compression member, a tension member, said members being generally U-shape in cross-section and each formed with a web and flanges at the sides of the web, and a journal box at each end of the frame and joined thereto adjacent the junction of the compression and tension members, the junctions between the frame and journal boxes being reinforced by ribs extending from those portions of the tension member adjacent the journal boxes diagonally upward across the outer faces of the side walls of the portions of the side frame above the journal boxes.

10. A car truck side frame comprising compression and tension members generally U-shape in cross-section, each formed with a web and flanges extending therefrom on opposite sides of the web, and a journal box at 50 each end of the frame and joined integrally thereto adjacent the junction of the compression and tension members, the junctions between the frame and the journal boxes being reinforced by flanges extending along 55 the faces of the side frame between the tension member and those portions of the side frame above the journal boxes, said flanges being increased in depth to a maximum adjacent the upper inner corners of the journal 60 boxes and decreasing in depth therefrom to their ends.

In testimony whereof I affix my signature.
BYERS W. KADEL.
